UNITED STATES PATENT OFFICE.

PETER J. O'BRIEN, OF TOLEDO, OHIO.

GLASS-BLOWER'S DUMMY.

No. 818,705.

Specification of Letters Patent.

Patented April 24, 1906.

Application filed July 6, 1905. Serial No. 268,417.

To all whom it may concern:

Be it known that I, PETER J. O'BRIEN, a citizen of the United States, and a resident of Toledo, in the county of Lucas and State of Ohio, have invented certain new and useful Improvements in Glass-Blowers' Dummies; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates especially to the class of machines employed in the manufacture of blown-glass articles and known as glass-blowers' "dummies" or "helpers," and it has for its object the provision of a simplified and improved form of apparatus of this character whereby its operation is facilitated and the work of the operator incident to the running of the same is reduced to a minimum.

Further objects as well as the operation, construction, and arrangement of the parts of the invention will be fully described in the following specification and shown in the accompanying drawings, in which—

Figure 1 is a top plan view; Fig. 2, a side elevation, and Fig. 3 a front elevation, of one form of machine embodying my invention.

Referring to the drawings, 1 represents an open tank or vessel of any suitable size or shape for retaining water, to the side of which is secured a bracket 2. Rising vertically from the horizontal arm of the bracket 2 are two spaced guide-rods 3, which have their lower ends threaded or otherwise suitably secured to said bracket and their upper ends rigidly connected by a cap-piece 3^a. A cross-head 4, having vertical openings to receive the guide-rods 3, is mounted to have a vertical reciprocating movement on said rods and is formed on its inner end with a downwardly-projecting arm, to which a glass-mold 5 is secured in suspended position to enable it to be entirely immersed within the water in the tank 1 when the cross-head 4 is lowered on the guide-rods 3. The mold 5 comprises two hinged sections, one of which is rigidly secured to the cross-head 4, while the other is adapted to have a pivotal movement relative to said first section and cross-head to enable the mold to be opened to permit the removal of an article after it has been blown. Projecting rearwardly from the cross-head 4 are

two arms 6, at the ends of which is carried a hollow tube or sleeve 7, which is disposed in substantial parallelism with the cross-head 4. Reciprocally mounted within the sleeve or tube 7, with one end projecting therefrom to the rear of the mold 5, is a rod 8, which has the upper surface of its extended end provided with two spaced lugs or spurs 9 to form a pocket or stirrup of suitable width to receive the toe of the operator's foot, thus enabling the rod to be reciprocated by an oscillatory movement of the foot. The purpose of the rod 8 is to open or close the mold and connects with the movable section thereof through the medium of the pivotal link 10. The rod 8 has its movement limited by reason of a pin 8^a thereon operating within a slot 7^a in the sleeve 7. Coiled compression-springs 3^b are mounted on one or both of the guide-rods 3 below and above the cross-head 4 to cushion the limits of movement thereof.

Fulcrumed to a stud 11, projecting from the bracket 2, is a lever 12, which has one end provided with a counterpoise 13 and its other end connecting with the cross-head 4 through the medium of the two pivotal links 14, the lever and links together forming a toggle, by means of which the cross-head is raised and lowered. The means shown for connecting the contiguous ends of the lever and links consist in forming a sleeve 15 in the end of the lever in which is secured by a cotter-pin or otherwise a short shaft 16, the ends of which are loosely mounted in bearings formed in the lower ends of the links 14, as shown in Figs. 1 and 3.

A lowering of the cross-head and connected parts for the purpose of causing an immersion of the mold 5 is effected by a pressure on the foot-treadle 17, which is adjustably secured to the treadle-rod 17^a and connects through it to one end of the lever 18, which is fulcrumed to the tank 1, and connects at its other end with the weight-arm of the lever 12 through the medium of the link 19, thus adapting a lowering of the treadle to raise the weight end of the lever 12 and cause a closing or converging movement of the toggles, which in turn lowers the cross-head and mold.

A platform 20, on which the operator stands and through which the treadle 17 projects, is mounted to the rear of the cross-head 4 with its forward edge in contiguous parallelism with the rod 8 and its surface substantially in a horizontal plane with that of

the upper surface of said rod when the cross-head is in normal or raised position.

The operation of the machine shown is as follows: Preparatory to blowing a glass article in the mold, the operator places the toe of the left foot between the spurs 9 on the rod 8 and by a movement thereof causes said rod to slide to the right within the sleeve 7, thus closing the mold and retaining it in that position during the blowing of the article therein. When the article has been blown, the operator moves his foot to the left to cause an outward movement of the rod 8 and an opening of the mold, which permits the removal of the blown article. After the article has been removed the operator causes the mold to be immersed in the water in the tank by pressing with his right foot upon the treadle 17, thereby causing the weight-arm of the lever to be raised and the cross-head and connected parts to be lowered by reason of the movement imparted to the links 14.

It will be apparent from this construction that the work entailed upon the operator is comparatively light compared with other machines of this class, inasmuch as he is not compelled to alternately raise first one foot and then the other to effect a raising or lowering of the mold and an opening or closing thereof as is customarily the case in this class of machines, which movement when continued for any length of time is very tiring to the operator. In my machine the workman has only one treadle to operate, while the opening and closing of the mold is effected by a simple side movement of the foot.

Having thus described my invention, what I claim as new, and desire to secure by Letters Patent, is—

- 40 1. In an apparatus of the class described, a water-tank, a vertically-movable member, a mold suspended from said member over the tank and having a hinged section, means for opening the mold, and means comprising a toggle and operating-treadle having connection with the toggle for effecting a lowering of said member and mold, said treadle passing through and above a platform disposed at the rear of and on a plane with the normal 45 position of the vertically-movable member.
- 50 2. In an apparatus of the class described, a

water-tank, a vertically-movable member, a two-part mold suspended from said member over the tank, means for opening the mold parts, toggle connection between said member and a fixed point in a vertical plane therewith, and means separate from the mold-opening means for effecting a movement of the toggle connection to cause a lowering of said member. 55

3. In a machine of the class described, a vertically-movable member, a mold suspended from said member and having a swinging part, personally-operated means for effecting an opening and closing of said mold, 60 and means for causing a lowering of said member, comprising a counterpoise-lever and a common lever in link connection, a foot-treadle connecting the common lever, and link connection between the counterpoise-lever and said member whereby a movement of the latter lever effects a movement of said member. 70

4. In a machine of the class described, the combination of a tank, a bracket secured to 75 the side of the tank, vertical guide members arising from the bracket, a member mounted to have a vertical movement on said guide members, a two-part mold suspended from said member over the tank, means carried 80 by said member for effecting an opening and closing of the mold, a counterpoise-lever pivoted below the bracket and having its light end formed with a bearing-head, two links pivoted at one end to opposite sides of the 85 bearing-head of the lever and having their other ends in pivotal connection with the movable member whereby to cause a lowering of said member as the weighted end of the lever is raised, a treadle mounted in a 90 platform at the rear of the movable member, and a lever and link connecting the treadle-rod and counterpoise-lever whereby to cause an elevation of the weighted end of the latter lever when the treadle is depressed. 95

In witness whereof I have hereunto signed my name to this specification in the presence of two subscribing witnesses.

PETER J. O'BRIEN.
